Primary Examiner — Kevin K Rudzinski*Assistant Examiner* — James P McKaneCLAIM

The ornamental design for a hoodie as shown and described.

DESCRIPTION

FIG. 1 is a perspective view of a hoodie showing my new design.

FIG. 2 is a front view of a hoodie.

FIG. 3 is a rear view of a hoodie.

FIG. 4 is a right side view of a hoodie.

FIG. 5 is a left side view of a hoodie.

FIG. 6 is a top view of a hoodie; and,

FIG. 7 is a bottom view of a hoodie.

The broken lines shown in the drawings depict portions of the hoodie in which the design is embodied that form no part of claimed design.
